JOSEPH H. BRYAN, OF BIRMINGHAM, ALABAMA, ASSIGNOR OF TWO-THIRDS TO
WALTER L. SIMPSON, OF BIRMINGHAM, ALABAMA

RADIATOR CABINET

Application filed April 25, 1929. Serial No. 358,132.

My invention relates to a radiator cabinet and has for its object the provision of a device for the character designated which is provided with a passage along the rear wall and cover of the cabinet, through which air may pass to become heated and humidified.

Another object of my invention is to provide, in cooperation with the rear wall of a cabinet, a passage at the rear and top thereof in which a humidifier is located and an insulating means along the inner side of the rear wall and cover of the cabinet to prevent an escape of heat from the passage to the rear and to create an induced draft of air through the passage and over the humidifier.

As is well known, steam heating radiators create a very dry atmosphere in a room unless some means be provided to supply moisture to the air. This has heretofore been accomplished, where radiator cabinets are employed, by placing a water pan within the cabinet and directly on top of the radiator. I have found that the rate of evaporation with such an arrangement is too rapid. If the size of the pan be made smaller, to lower the quantity of vapor supplied to the air, the water is soon evaporated from the pan and it is neglected so that the purpose of the humidifier is defeated.

It is accordingly the prime object of my invention to provide a radiator cabinet embodying a humidifier and in which the rate of evaporation is maintained relatively low, whereby a pan of relatively large capacity may be employed without supplying too much moisture to the air and which will require refilling at infrequent intervals.

The above object is accomplished by the provision of a passage at the rear and extending across the top of the cabinet and in which the humidifier is located. The passage is separated from the radiator by metal partitions whereby the rate of heat transfer to the humidifier is lessened. In addition, means are provided for creating a draft of air through the passage and over the humidifier.

My invention comprises further novel features, and details of construction, as will

be hereinafter set forth and shown in the accompanying drawings, wherein

Fig. 1 is a perspective view of my improved radiator cabinet;

Fig. 2 is a sectional view taken along the line II—II of Fig. 1; and

Fig. 3 is a sectional view taken along the line III—III of Fig. 2.

Referring to the drawings, I show a cabinet 5 which is adapted to enclose a radiator 6 as shown in Fig. 2 of the drawings. The cabinet is formed having a front wall 7 having grilled openings 8, side walls 9 and 11, a rear wall 10 and a cover 12. A horizontal metal partition 13 is secured to the side walls and the front wall to form a horizontal passage 14 along the top of the cabinet. A vertical metal partition 16 is secured at its upper end to the horizontal partition, at its sides to the side walls 9 and 11 and at its base to the rear wall 10 to form a vertical passage 17 merging with the horizontal passage. A number of spacer blocks 18 are interposed between the rear wall and partition 16 and secured in position by means of bolts 19 passing therethrough which are adapted to engage the rear wall and partition to add rigidity thereto. The lower end of the partition 16 is turned outwardly and joined to the rear wall 10 of the cabinet to prevent dust laden air entering the bottom of the cabinet from passing upwardly into the passage 17.

A number of openings 20 are formed in the rear wall 10 to allow a free passage of air into the lower end of the vertical passage 17 for air which rises through the vertical passage 17 and out through the horizontal passage 14.

A humidifier comprising a water pan 21 is mounted on the horizontal metal partition 13, and in the horizontal passage, to humidify the air passing therethrough and is made accessible by hinging the cover 12 as at 22.

The rear wall 10 and the cover 12 are insulated on their inner sides by means of any suitable heat insulating material 23 to prevent the escape of heat from the passages 14 and 17 and also to protect the outer painted surfaces by maintaining them in a relatively

cool state. It is well known that people are accustomed to placing flower vases, etc., upon this form of cabinet and the outer surface of the cover is soon marred if it is not kept in a cool state.

A pair of hand holes 24, only one of which is shown, are formed in the horizontal partition 13, being located one on each side of the humidifier, and provided with suitable covers 25 which are hinged at 26 to provide an access to a radiator valve 30. It is necessary to provide a hand hole on each side of the cabinet as the radiator valves are provided on either side of radiators.

15 In use, the cover 12 is first raised to allow access to the water pan 21 which is to be filled with water, after which, the hand hole cover 25 is raised to allow access to the radiator valves to turn on the steam. As 20 the air in the vertical passage 17 becomes heated it will rise and pass over the humidifier, mounted in the horizontal passage 14, to absorb water therefrom and then pass through the grille 8 to heat and humidify 25 the air in the room. As the air rises in the vertical passage it will draw cold air through the openings 20 which are located at a suitable distance from the floor to avoid drawing dust and dirt therefrom.

30 It will be seen that the location of the humidifier in the passage where it is separated from direct contact with the radiator reduces the temperature to which it would otherwise be subjected, while the induced 35 current of air flowing over it provides sufficient cooperation and moisture for the room.

While I have shown my invention in but one form, it will be obvious to those skilled in the art that it is not so limited but is susceptible of various changes and modifications without departing from the spirit thereof and I desire therefore that only such limitations shall be placed thereupon as are imposed by the prior art, or as are specifically set forth 45 in the appended claims.

What I claim is:

1. In a radiator cabinet embodying end walls, a rear wall, a grilled front wall and a cover, a vertical partition secured in spaced 50 relation to the rear wall to form a vertical passage, a horizontal partition secured in spaced relation to the cover to form a horizontal passage merging with the vertical passage and opening through the grilled front 55 wall, a water pan mounted on the horizontal partition, means for insulating the inner side of said rear wall and cover throughout the passages, and hand holes provided in the horizontal partition to facilitate the operating of the radiator valves.

2. In a radiator cabinet embodying end walls, a rear wall, a grilled front wall and a cover, a vertical partition secured in spaced 60 relation to the rear wall to form a vertical 65 passage and being joined to the rear wall at

the bottom to close it to the interior of the cabinet, said rear wall being provided with holes for the admission of cold air to the bottom of the vertical passage, a horizontal partition secured in spaced relation to the cover to form a horizontal passage merging with the vertical passage and opening through the grilled front wall, a water pan mounted on the horizontal partition, and means for insulating the inner side of said rear wall 70 and cover throughout the passages.

I testimony whereof I affix my signature.

JOSEPH H. BRYAN.
